UNITED STATES PATENT OFFICE.

RUDOLPH HOFFMAN, OF CLEVELAND, OHIO.

BURNER.

Application filed October 26, 1925. Serial No. 64,742.

This invention relates to burners for oil stoves and has for one of its objects the provision of an improved form of air distributor and flame spreader for use in connection with an annular wick, that will be of simpler construction and less expensive to manufacture than the devices heretofore used, without lowering the efficiency of the burner.

10 A further object of the invention is to provide an air distributor for the interior of the wick tube that is so constructed that it will be accurately positioned and held so that it will not be displaced by the wick, the parts being also arranged so that they will be held in an inoperative position when not properly located in the wick tube, and the fact that the parts are not properly assembled will be readily perceived by the operator.

20 Other objects of the invention and the features of novelty will be apparent from the following description taken in connection with the accompanying drawings, in which:

Fig. 1 is an elevation of a burner embodying my invention, with certain parts shown in longitudinal section;

Fig. 2 is a longitudinal section through the wick tube, the air distributor and flame spreader unit being shown in the inoperative position in which the unit will be held when the parts are not properly assembled;

Fig. 3 is a bottom plan with certain parts in section;

Fig. 4 is a plan view of the air distributor with the flame spreader removed;

Fig. 5 is a perspective view of an air distributing ring of slightly different construction from that illustrated in the other figures embodying my invention;

Fig. 6 is a view similar to Fig. 1 but showing another form of the invention;

Fig. 7 is a bottom plan view thereof; and

Fig. 8 is a vertical section through the air distributor.

Referring to the drawings, 10 indicates the outer wick tube and 11 the inner wick tube which are spaced apart, according to the usual practice, to provide an annular space for the wick 12. The inner wick tube is formed with a ledge 13 for a purpose to be hereinafter described and has secured, below this ledge, a plurality of radially extending wings or vanes 14 which are formed with the central raised portions 15, as

shown. A flame spreader 16, in the form of a disk, has its peripheral portion 17 arranged above the wick 12 and this flame spreader is provided with perforations 18 and is secured to a plurality of radially extending wings or vanes 19 by means of tangs 20 which project through openings in the flame spreader 16. The lower edges of the vanes 19 are adapted to engage with the ledge 13 for the purpose of supporting the parts in proper relation to the upper edges of the wick tubes, and are also recessed as indicated at 21 to permit the vanes 19 to clear the raised portions 15, of the vanes 14, when the unit, of which the flame spreader 16 and vanes 19 are a part, is rotated. A locking member 22 is secured to the vanes 19 at the center of their lower edges and is provided with slots 23 through which the raised portions 15 are adapted to pass when said unit is lowered into position. The raised portions 15, of the vanes 14, are provided with downwardly faced abutments 24 with which the member 22 is adapted to interlock, upon being slightly rotated, for the purpose of preventing said unit from being raised by the wick, when the latter is projected above the wick tube.

The upper portions of the side edges of the vanes 19 are provided with notches 25 in which an air distributing ring 26 is carried, this ring being substantially V-shaped in cross-section with a frusto-conical portion extending inwardly and upwardly from the upper edge of the inner wick tube.

The vertical edges of the vanes 19 closely fit the interior of the wick tube 11 so as to accurately center the flame spreader 16 and air distributing ring 26 and the periphery of the latter also closely fits within the wick tube 11 so as to form an air barrier that will compel the greater portion of the current of air that rises through the tube 11 to pass around and above the ring 26. For efficient operation of the burner, I have found that it is essential to provide a restricted supply of air directly over the upper edge of the inner wick tube and, for this purpose the periphery of the ring 26 is provided with small notches 27 which will permit a restricted flow of air therethrough.

In the modified form of air distributors, shown in Fig. 5, there is a short corrugated flange 28 on the periphery of the ring, the corrugation providing air passages that function in the same manner as the notches 27.

The parts are shown in their normal relation in Fig. 1 and the unit comprising the vanes 19, the flame spreader 16 and the ring 26, is securely held in this position by the engagement of the member 22 with the abutment 24 so that, in case the wick 12 is raised sufficiently to engage the periphery 17 of the frame spreader, it will not displace this unit from its normal setting. When the unit is inserted into the tube 11, the member 22 will engage with the raised portions 15, of the vanes 14, unless the notches 23 happen to register with these raised portions. The engagement of the member 22 with the portions 16 serves to hold said unit in the position shown in Fig. 3 and it will be perfectly apparent to the operator that the unit is not properly positioned. However, it will only be necessary to slightly rotate the unit 20 to register the notches 23 with the portions 15, of the wings 14, to permit the unit to drop to its normal position shown in Fig. 1. Then a slight rotation will interlock the member 22 with the abutments 24.

25. In the form of the invention illustrated in Figs. 6 to 8, there is secured to the ledge 13 a ring 30 having perforations 31 therein to permit the passage of air, said ring, in effect, being an extension of the ledge 13 30 and having a plurality of notches 32. The air distributor comprises a plurality of wings 33, the outer edges of which fit within the inner wick tube 11 for the purpose of centering the air distributor unit. The 35 wings 33 carry the flame spreader 16 and have their lower ends bent horizontally to form feet 34 which engage with the ledge 13 and thus support the unit. The feet 34, of the wings 33, have downwardly projecting extensions 35, of hook-like form which extend through the openings 32 and engage with the underside of the ring 30, whereby the air distributor unit is locked in position and prevented from being raised by the 45 wick. When the air distributor unit is inserted in the inner wick tube 11, the extensions 35 pass through the openings 32 and the unit is then rotated to the position in Fig. 7 in which the extensions 35 are interlocked with the ring 30.

In this form of the invention, I have also illustrated a slight modification of the construction of the air barrier 26, of the construction first described. In the modified 55 construction, the air barrier 36 consists of a frusto-conical ring having notches 37 in its periphery, this ring being seated in recesses 38 in the wings 33 and the construction differing from that illustrated in Fig. 1 in that 60 the vertically extending flange, of the latter, is omitted.

Having thus described my invention, I claim:

1. In burners of the class described, the 65 combination of inner and outer wick tubes

forming an annular wick space therebetween, said inner tube having a ledge on the interior thereof, a flame spreader arranged above said tubes with its periphery projecting over said space, vertically disposed 70 transversely extending members to which said spreader is attached, said members resting on said ledge, and a frusto-conical air barrier carried by said members and closely fitting the interior of said inner tube, said 75 air barrier projecting upwardly and inwardly from the upper edge thereof.

2. In burners of the class described, the combination of inner and outer wick tubes forming an annular wick space therebetween, said inner tube having a ledge on the interior thereof, a flame spreader arranged above said tubes with its periphery projecting over said space, vertically disposed 80 transversely extending members to which said spreader is attached, said members resting on said ledge, and a frusto-conical air barrier closely fitting the interior of said inner tube and projecting upwardly and inwardly from the upper edge thereof, and 85 said air barrier being provided with restricted marginal recesses for supplying air through said barrier directly to the inner edge of said wick space.

3. In burners of the class described, the combination of inner and outer wick tubes forming an annular wick space therebetween, said inner tube having a ledge on the interior thereof, a flame spreader arranged above said tubes with its periphery projecting over said space, vertically disposed radial vanes to which said spreader is attached, said vanes fitting within the inner tube and resting on said ledge, and a frusto-conical air barrier carried on said members and closely fitting the interior of said inner tube 100 and projecting inwardly and upwardly from the upper edge thereof.

4. In burners of the class described, the combination of inner and outer wick tubes forming an annular wick space therebetween, said inner tube having a ledge on the interior thereof, a flame spreader arranged above said tubes with its periphery projecting over 105 said space, vertically extending members to which said spreader is attached and resting on said ledge, and a frusto-conical air barrier carried on said members and closely fitting the interior of said inner tube and projecting inwardly and upwardly from the upper edge thereof.

5. In burners of the class described, the combination of inner and outer wick tubes forming an annular wick space therebetween, said inner tube having a ledge on its interior, and a combined flame spreader and air barrier unit comprising a plurality of vanes rest- 110 115 120 125 130

ing on said ledge, a disk secured to said vanes and having its peripheral portion arranged over said wick space and a frusto-conical ring carried on said vanes with its periphery 5 closely fitting the interior of said inner tube at its upper end, said ring being provided with peripheral recesses through which air is supplied to the inner edge of the wick space.

10 6. In burners of the class described, the combination of inner and outer wick tubes forming an annular wick space therebetween, said inner tube having a ledge on its interior, and a combined flame spreader and air barrier unit comprising a plurality of vanes resting on said ledge, a disk secured to said vanes and having its peripheral portion arranged over said wick space and a frusto-conical ring carried on said vanes 15 with its periphery closely fitting the interior of said inner tube at its upper end, said ring being provided with peripheral recesses through which air is supplied to the inner edge of the wick space, and interlocking 20 means carried by said inner tube and said vanes for preventing said unit from being lifted from its normal position by the wick.

25 7. In burners of the class described, the combination of inner and outer wick tubes forming an annular wick space therebetween, a combined flame spreader and air barrier unit arranged within said inner wick tube and extending above the same, a ledge on 30

the interior of said inner wick tube, and a combined supporting and locking means in 35 relatively fixed relation on said unit engaging the upper and lower sides of said ledge.

8. In burners of the class described, the combination of inner and outer wick tubes forming an annular wick space therebetween, 40 a combined flame spreader and air barrier unit arranged within said inner wick tube and extending above the same, a ledge on the interior of said inner wick tube, and said unit having circumferentially spaced supporting members engaging the upper side of 45 said ledge and provided with hooks engaging the lower side of the ledge to lock said unit in position.

9. In burners of the class described, the combination of inner and outer wick tubes forming an annular wick space therebetween, 50 a combined flame spreader and air barrier unit arranged within said inner wick tube and extending above the same, a circular 55 ledge on the interior of said inner wick tube provided with circumferentially spaced openings, and said unit having supporting members engaging the upper side of said ledge and having hook-like extensions projecting through said openings and engaging the lower side of the ledge to lock said unit 60 in position.

In testimony whereof, I hereunto affix my signature.

RUDOLPH HOFFMAN.
